United States Patent Office

Des. 228,439

Patented Sept. 25, 1973

228,439

PLATE OR THE LIKE

Ottorino N. Mercadante, Corning, N.Y., assignor to Corning Glass Works, Corning, N.Y.

Filed Sept. 21, 1971, Ser. No. 182,570

Term of patent 14 years

Int. Cl. D7—01

U.S. Cl. D7—36

Fig. 1

Fig. 2

FIG. 1 is a top plan view of a plate or the like of conventional configuration showing my new design.

FIG. 2 is an enlarged fragmental view of the plate and design shown in FIG. 1.

I claim:

The ornamental design for a plate or the like, as shown and described.
